[57] CLAIM

The ornamental design for an auxiliary light for vehicle
having attached plow blade, as shown and described.

DESCRIPTION

FIG. 1 is a side pictorial view of an auxiliary light for
vehicle having attached plow blade showing my new
design;

FIG. 2 is a front elevational view thereof;

FIG. 3 is a right side elevational view thereof which is
similar to the left side elevational view; and,

FIG. 4 is a top plan view thereof; and,

FIG. 5 is a rear elevational view thereof.

The mounting elements are shown in broken line in
FIG. 3 for illustrative purposes only.

FIG. 4

FIG. 1

FIG. 3

FIG. 2

FIG. 5
